UNITED STATES PATENT OFFICE.

FRANK FOLEY, OF MAYVIEW, ARKANSAS.

PROPELLER.

1,355,758.

Specification of Letters Patent. Patented Oct. 12, 1920.

Application filed June 10, 1918. Serial No. 239,220.

To all whom it may concern:

Be it known that I, FRANK FOLEY, a citizen of the United States, and a resident of Mayview, in the county of Arkansas and 5 State of Arkansas, have invented certain new and useful Improvements in Propellers, of which the following is a specification.

My invention is an improvement in propellers, and has for its object to provide a device of the character specified especially adapted for use in flying machines, wherein the propeller has a blade of spiral form, so arranged that the pitch of the blade may be 10 varied.

In the drawings:

Figure 1 is a top plan view of one embodiment of propeller construction;

Fig. 2 is a top plan view of another embodiment of the invention;

Fig. 3 is a side view of Fig. 1;

Fig. 4 is a front view of one of the propellers showing the mounting;

Fig. 5 is a side view of Fig. 4 in closed 15 position.

The improved propeller is mounted upon a shaft 1, and the propeller is composed of similar sections, each section being approximately a half circle. In Fig. 1 each section 20 is composed of concentric arch bars 2, 3 and 4, and spokes 5 connect the arch bars. Each spoke 5 is double, extending on both sides of the propeller shaft, and each spoke has a hub 6 which engages the propeller shaft, the 25 hub being at the center of the spoke. The end spokes 5 of each wing section are continuous with the opposite spoke of the other wing section, and the same statement applies to the intermediate spokes, that is, 30 each spoke, or each double spoke, forms a part of both wing sections.

A suitable cover 8 is provided for each wing section, the said cover being supported by the arch bars and the spokes.

45 The uppermost spoke 5 is fixed to the shaft 1, and it is guyed by guy wires 9 which extend from a head 7 on the upper end of the shaft to the opposite ends of the spoke. The hubs of the other spokes are 50 slidable on the shaft, and flexible members 10, as, for instance, cords or cables, are connected with the lowermost spoke and with the arch bars 2 for pulling the lowermost spoke downwardly to increase the pitch of 55 the blade formed by the propeller sections.

It is obvious that when the lowermost

spoke moves upwardly the pitch will be lessened, while when the spoke is moved downwardly the pitch will be increased. Any suitable operating means may be connected 60 with the cords 10 for controlling the same.

In Fig. 2 is shown a modified form of propeller. In this arrangement each of the sections consists of arc shaped bars 11, 12 and 13, which are connected by spokes or radial bars 14, the said spokes being double in the same manner as in the construction of Fig. 1. Each double spoke has a hub 15 at its center for engaging the shaft 1, and the innermost arch bars 13 are somewhat greater 65 than a semicircle, so that the ends of the said bars overlap, and each end of each bar is connected to the adjacent end of the bar 14 by means of a spoke 16. The ends of the arch bar 12 are also connected with these 70 spokes 16.

A suitable covering 17 is supported by the spokes and the arch bars, and the operation of the construction shown in Fig. 2 is precisely the same as that shown in Fig. 1. 80 When it is desired to increase the pitch of the propeller blades the cords 10 are drawn downward and when the tension on the cords is relaxed the natural resiliency of the bars from which the propellers are 85 formed will tend to cause them to return to original position.

The operating mechanism for increasing or decreasing the pitch of the blades consists of a sleeve or collar 18 mounted upon 90 the propeller shaft 1, and this sleeve has pulleys 19 over which the flexible members 10 pass. Each of the sleeves or collars 18 has pivoted thereto a link 20 and the other end of each link is connected to one end of 95 a lever 21 pivoted at its inner end to a brace 22 on the frame 23 which supports the propeller shaft.

A flexible member 24, as, for instance, a cord or wire, has one end connected with 100 the lever 21 near the link and each of the cords passes over direction elements 25 of a reel 26 upon which the other end of the cord winds.

It will be evident that when the reel is 105 operated in the proper direction by means of the crank 27 connected therewith the sleeve will be drawn downwardly, thus increasing the pitch of the propeller. The propeller shafts are rotated by means of 110 bevel gearing 28 from a suitable driving shaft 29.

I claim:

In a flying machine, a propeller comprising in combination with the shaft, a series of bars, each having a hub at its center 5 mounted to slide on the shaft, said bars being arranged in spaced relation and extending on opposite sides of the shaft, a flexible covering secured to the bars at each side of the shaft, means for anchoring the upper

bar, means for drawing down the lower bar, 10 and a connection between said bars for holding them in vertically spaced relation when they are moved downwardly.

FRANK FOLEY.
